Primary Examiner—Lucy Lieberman(74) Attorney, Agent, or Firm—Scully, Scott, Murphy & PresserCLAIM

The ornamental design for a liquid and lotion applicator, as shown and described.

DESCRIPTION

FIG. 1 illustrates a bottom plan view of a liquid and lotion applicator showing my new and ornamental design, FIG. 2 is a top plan view of the liquid and lotion applicator; and,

FIG. 3 is a side view of the liquid and lotion applicator, the opposite side is a mirror image thereto except for the continuous screw threading on the neck and the diagonal lines on the handle of the raised tennis racket.
